UNITED STATES PATENT OFFICE.

WILLIAM C. STEWART, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

STARTING AND STOPPING MECHANISM.

Application filed December 14, 1918. Serial No. 266,756.

To all whom it may concern:

Be it known that I, WILLIAM C. STEWART, a subject of the King of England, residing at Swampscott, in the county of Essex and 5 State of Massachusetts, have invented certain Improvements in Starting and Stopping Mechanisms, of which the following description, in connection with the accompanying drawings, is a specification, like 10 reference characters on the drawings indicating like parts in the several figures.

This invention relates to starting and stopping mechanisms and, particularly, to starting and stopping mechanisms constructed 15 and arranged to effect either a predetermined number of machine cycles and then stop automatically, or, at the will of the operator, to effect continuously and uninterruptedly an indefinite number of cycles. 20 The invention is illustrated and described herein as applied to a perforating machine of the type shown in United States Letters Patent No. 955,711, although it is not restricted to such use.

25 In a common use of machines of this type for making perforated designs upon the vamps, tips or other portions of shoe uppers, it is often desired, owing to sharp changes in the curvatures of the designs that are 30 used, to locate the work carefully before each perforation is made. For such use it is desired that the machine be capable of stopping after a single perforation only has been made, so as to permit relocating the 35 work for the succeeding perforation in order to follow accurately the desired outline. However, on other portions of the work, as when the outline is straighter, the machine may properly be run uninterruptedly at a 40 high rate of speed and many perforations be made before it is necessary to stop the machine.

45 As such machines have been organized heretofore, they have not satisfied the modern requirements of the trade for high speed of operation for the following reasons, among others: First, with increased speed the strain placed upon the clutch has been so great as to cause excessive breakage of 50 parts, and second, it is very difficult, if not almost impossible even at relatively moderate speeds, to operate a controlling

treadle quickly enough to cause the machine to have only a single cycle when no more are desired. This often causes considerable 55 damage to the work because additional perforations are made in wrong positions before the work can be relocated. In perforating machines of the said type, a speed of 700 to 800 revolutions per minute has 60 been found to be practicable but this speed is considerably too high for any but expert operators to "catch" the clutch when only a single revolution or cycle of the machine 65 is desired.

An object of the present invention is to provide a starting and stopping mechanism adapted, among other uses, to be incorporated in a machine of the type above mentioned, which mechanism will be organized 70 to provide for properly stopping the machine even at high speeds after a single revolution or after a single cycle only, but which may also be operated uninterruptedly whenever repeated cycles are desired. 75

Another object of the invention is to provide a mechanism which will come to a full stop promptly but in a comparatively gradual manner so that the parts will not be broken, even at high speeds. To insure 80 positive stopping without undue shock or strain, the organization is such that the effective braking force of the mechanism increases proportionately to increases in machine speed. 85

Starting and stopping mechanisms have been designed in which a machine may be run continuously by a partial depression of the treadle and may be caused to have only a single cycle upon a complete depression 90 of the treadle. Such mechanisms have been used principally in slow speed machines, such as punch presses and the like. This mode of operation, however, would be particularly undesirable and even dangerous 95 in a perforating machine, or other high speed machine, because the machine would have more than one cycle unless the treadle were completely depressed to the full extent of its stroke before the machine had 100 passed through a complete cycle. To meet this objection, the starting and stopping mechanism of the present invention is so constructed and arranged that a partial de-

pression of the treadle, or a partial movement of other manually controlled means, will cause the machine to have only one cycle and only by particular conscious effort upon the operator's part can the machine be caused to have, uninterruptedly, an indefinite number of cycles, this being accomplished by a more extended depression or movement.

10 To make the starting and stopping mechanism more convenient by eliminating unnecessary movements of the treadle, the mechanism is so constructed and arranged that after a single cycle, or at any time 15 that the treadle is in midposition, a more extended depression of the treadle will cause the machine to run uninterruptedly while a partial return of the treadle, as to its mid-position, will stop the machine. Thus 20 it is not necessary to return the treadle to the upward limit of its movement and then to make a full downward stroke to control the machine each time several cycles are desired, although this can be done if desired. After a single cycle, or at any time 25 that the treadle is in mid-position, a further single cycle of the operations may be secured by raising the treadle to its uppermost position and then depressing it again to 30 mid-position.

It is important, in the operation above described, that the operator be able to feel when the treadle is in its mid-position. To this end, in the illustrated construction, an 35 additional resistance to the movement of the treadle is provided when this position is reached on its downward movement sufficient to apprise the operator of the mid-position. This additional resistance is removed when the mid-position is reached on 40 the upward stroke. The operator is thus always enabled to ascertain when the treadle is in the mid-position by noting the point at which this additional resistance is met with 45 or is removed.

In accordance with other features of the invention, the illustrated starting and stopping mechanism comprises a brake drum and a brake band constructed and arranged 50 to revolve with the brake drum during the operation of the machine and to have a limited rotation relative thereto during the stopping of the machine, the mechanism being so designed that a continually increasing force is applied to the brake drum until the forward movement of the machine 55 has been arrested so that the machine is stopped in a comparatively gradual manner, while stopping of the machine is assured because the mechanism is so arranged 60 that the force applied to the drum increases when it is necessary to overcome increased momentum due to higher running speeds of the machine.

It has been usual in mechanisms of the 65 general type above-mentioned to have a brake which is applied to the shaft before the clutch is released and such brake usually remains in operation until after the 70 machine has been started again, thus putting unnecessary loads upon both the driving means and the brake. By the present invention, however, this difficulty has been overcome by arranging the brake so that it 75 is not applied until the time that the clutch is disengaged or slightly thereafter and the brake is released at the time that the clutch is engaged for starting.

These and other features of the invention, including various combinations and parts 80 and details of construction will now be described in connection with the accompanying drawings forming part of this specification.

In the drawings:—

Fig. 1 shows the starting and stopping mechanism applied to the perforating machine of the patent referred to above;

Fig. 2 shows a rear end elevation of said mechanism;

Fig. 3 is a sectional view of the clutch and brake parts taken along the line 3—3 in Fig. 2;

Fig. 4 is a sectional view of a portion of the clutch and brake parts taken along the 95 line 4—4 in Fig. 3;

Fig. 5 is a perspective view of the starting and stopping mechanism; and

Figs. 6, 7, 8 and 9 show details of construction to be described.

The machine is provided with a stepped driving pulley 20 which is loose upon the shaft 22 but which may be engaged therewith by means of a "Horton" clutch. This clutch consists of the usual cam member 24 secured to the shaft by means of a pin 26. Upon a cylindrical portion of the cam member is mounted the usual roller cage 28, one of the rollers being shown at 30. When permitted, the roller cage is forced forward in the direction of rotation of the pulley by means of a compression spring 32 to cause the rollers to clutch together the pulley and cam member and drive the machine forward in the manner usual with such clutches. The movement of the cage is limited by the ends of a slot 36 in the cage striking against a pin 34 located in the cam member 24. The roller cage is moved relatively backward to unclutch the rollers when the lug 38 on the cage is permitted to strike a stop dog 40, which may be moved into or out of operative position in a manner to be described. The stop dog is yieldingly mounted upon a rod 42, the yielding movement being permitted by means of a compression spring 43 mounted on the rod above the dog, and the amount of initial compression given to the

spring being adjusted by means of a nut 44 and check nut 46. The clutch and its disengaging mechanism above described is that usual in "Horton" clutches and forms no part of the present invention, per se.

The machine is started by swinging the rod 42 so that the dog 40 becomes disengaged from the lug 38, thus permitting the roller cage to spring forward and cause the pulley 10 and shaft 22 to be clutched together by means of the rollers 30 and the cam member 24. The mechanism for swinging the rod 42 will now be described:—When the treadle rod 47 is depressed, the rear end of a pivoted 15 lever 48 is raised. This lifts a pin 49 slidably mounted in the frame of the machine, (see Fig. 9). This pin engages a lever 50 fixed to the shaft 52. In this manner, when the treadle rod 47 is depressed, the shaft 52 is turned, against the resistance of the 20 spring 53, to a limited extent in a clockwise direction (see Figs. 2 and 9) and this swings a lever 54 attached to the shaft 52 so that a notched member 56, pivoted on the 25 lever 54 and engaging an ear 59 on a latch 58, moves the latch in a counter clockwise direction. This latch then becomes disengaged from a latch plate 60 mounted upon a projection 61 of a cam lever 62, causing the 30 machine to start, as will be explained later. The cam lever 62 is a portion of a swinging member 64 mounted to swing freely upon the shaft 52. The swinging member 64 has an extension 66 in which the rod 42, 35 above mentioned, is mounted and also has another extension 68 for a purpose to be described. This swinging member has a U-shaped portion 70 which straddles a bearing 72 extending from the frame of the 40 machine, which bearing forms a support for the shaft 52. A compression spring 74 tends normally to swing this member in a clockwise direction but it is restrained from doing so by the engagement of the latch 58 with the 45 latch plate 60. When the treadle is depressed and the latch 58 is disengaged, the member 64, forced by the compression spring 74, swings in a clockwise direction and disengages the dog 40 from the lug 38, thereby 50 starting the machine. The swinging of the member 64 carries the extension 68 thereof into such a position that the stud 80, mounted on said extension, strikes the notched member 56 and swings it about its pivot 82, 55 against the action of the tension spring 83, so that its engagement with the latch 58 in the notch 84 is released, the engagement being transferred to the lower notch 86. Then the latch 58, moving in the notch 86, is 60 forced towards its original position by means of a coiled spring 88. However, owing to the movement of the swinging member 64, the latch plate 60 is above latching position and the latch 58 is spring pressed against the 65 projection 61 of the swinging member 64,

ready to engage the latch plate 60 as soon as the projection 61 is brought down into locking position. The swinging of the member 64 caused by the compression spring 74, also carries the cam roll 76, on the cam lever 70 75 into engagement with a cam 78 mounted on the shaft 22 of the machine. As the shaft and cam have now started to revolve, (because the stop dog 40 has been disengaged) the cam lever 62 is operated by the cam 78 to swing the swinging member 64 back towards its original position. When this movement has continued sufficiently, the latch plate 60 is brought into position to be locked by the latch 58. The swinging member 64 is thus 80 locked in a position so that the stop dog 40 is in position to disengage the clutch and stop the machine at the completion of a single revolution.

All of the above operations have been contingent upon the fact that the treadle rod has been only partially depressed and the lever 54 made only a portion of its possible movement. The operator is enabled to determine this position of the treadle by means of a spring-pressed stop plunger 90 located in an arm 92 of the lever 50 fixed to the shaft 52, the plunger engaging the frame of the machine when the treadle has been depressed sufficiently to cause the above-named operations to take place. This position of the treadle rod may conveniently be called its "mid-position" and may be adjusted by means of the nuts 95.

If the operator wishes to have the machine 100 run continuously, after the treadle is in its mid-position, a more extended movement is given thereto, an additional pressure being required thereon to overcome the resistance of a spring 93 behind the plunger 90. When the treadle is depressed to its full downward limit, determined by the adjustable stop screw 94 striking the frame 96 of the machine, the notch 86, with which the ear 59 of the latch 58 has been or will be engaged 110 by the first revolution of the machine, will, on account of the more extended clockwise movement of the lever 54, be in a position to hold the latch 58 in inoperative position 115 so that the swinging member cannot be locked in position. The swinging member 64, therefore, is moved continuously, the cam 78 moving it in one direction and the spring 74 moving it in the other direction. However, as the cam roll 76 is on the low part 120 of the cam whenever the lug 38 is opposite the stop dog 40, the stop dog can not come into contact with the lug and so the clutch cannot become disengaged. Accordingly, the machine will run continuously until the operator allows the treadle to return to either its mid or uppermost position. When the treadle is returned to either of these positions, the lever 54 is brought back to a 125 position to permit the latch 58 to engage 130

the latch plate 60 so that the stop dog 40 will be held in position to engage the lug 38 and stop the machine as soon as the stopping position is reached. If the treadle rod is returned only to mid-position, the ear 59 of the latch 58 remains in engagement with the notch 86, but, if the treadle rod is returned to its uppermost position, the ear 59 slips out of engagement with said notch and into engagement with the notch 84, the spring 83 snapping the lever 56 into this position; in either case the parts are left in proper position for subsequent operations of the treadle rod in the manner before described.

In order to stop the machine smoothly when the stop dog operates, a band brake device is employed. This is of novel construction and constitutes an important feature of the invention. By its use it is possible to stop the machine smoothly, even when running at a high rate of speed. Its construction and operation will now be described:—

A brake drum 100 is employed, which, for convenience, is made as an enlarged integral portion of the cam member 24, fixedly mounted upon the main shaft 22 that it is desired to stop. Co-operating with this brake drum is a brake band consisting of a flexible metal band 101 to which is secured a leather facing 102. The operation of the brake band is unusual in that it is arranged to revolve with the brake drum and is also arranged to have, at times, a limited relative angular movement thereto, as will be explained in detail later. In order to maintain the band in position, it is prevented from movement in a direction longitudinally of the shaft by means of a flange 104 on one side and on the other side by means of a cover plate 106 forming a similar flange. To prevent it from being thrown off the drum by centrifugal force its ends are loosely connected together by a link 108. This link is fastened to the ends of the band by pins 110 and 112, the latter one of which operates in a slot in the link to permit the band to expand and contract to release or apply braking action to the drum. The band is yieldingly held in angular position relatively to the drum by means of a tension spring 114, (shown broken away in the drawings) one end of which is fastened to the pin 112 on the band and the other end of which is fastened to a pin 116 fixed relatively to the brake drum and located in a lug on the cover plate 106. As the pin 116 is ahead (in the direction of rotation) of the pin 112, the band 101 is held by the spring 114 in its most forward angular position relatively to the brake drum, this position being limited and determined by a projection 118 on the band engaging a notch 120 of the cover plate 106. When relative rotation between the band and drum occurs, as will appear later, the projection 118 is separated

from the face 120 and the relative rotation or angular displacement, if not otherwise prevented, may occur until another projection 122 on the brake band engages the edge 124 of the cover plate (see Fig. 5). Two oppositely hook-shaped projections 126 and 128 are located respectively one on each end of the band. The end carrying the projection 126 will be called the forward end because it is the end that first reaches a given point during rotation. The projection 126 is similar to the lug 38 on the roller cage and when the machine is to be stopped, said projection 126 engages the stop dog 40 in a manner similar to but, preferably, at a time slightly later than, the lug 38 (i. e. after the clutch is disengaged). This engagement of the stop dog and projection 126 causes the brake band to wrap around the brake drum in a manner similar to the action of a rope around a capstan, this action being due mainly to the spring 114. The faster that the machine is revolving the greater this wrapping and consequent braking action becomes. This is due to the fact that, when the speed of the machine is increased, the momentum of the brake band is increased, causing the yielding spring 43 to be compressed to a greater extent upon engagement of the stop dog 40 with the projection 126 on the brake band 101 so that a greater force is exerted upon the band. Furthermore, the momentum at higher speeds allows the shaft to revolve to a greater extent before stopping, which causes the pin 116 to move to a greater distance relatively to the pin 112, stretching further the spring 114 and producing a greater pull upon that end of the band. The springs 114 and 43 acting in opposition to each other upon opposite ends of the brake band to contract it causes, therefore, a greater braking force to be exerted upon the brake band to stop the machine when the machine is being run at higher speeds. With this novel construction, the machine is stopped comparatively gradually, without undue shock or vibration, because, during the stopping operation, the springs 114 and 43 are acting with a continually increasing force upon the brake band until the forward movement of the machine is arrested. These parts are adjusted so that the forward movement of the machine is normally stopped before the brake drum has advanced relatively to the brake band sufficiently to bring the edge 124 on the cover plate into engagement with the projection 122 on the brake band, but such engagement would finally arrest the forward movement of the machine if the brake band should fail to operate properly.

The movement of the swinging member 64 which brings the stop dog 40 into operative position also brings a latch 130, which is pivotally mounted on said member, into opera-

tive position. When in this position, the latch will yield because of the spring 131, and permit both hook-shaped projections 126 and 128 of the brake band to pass by it when the brake band moves forward. It will, however, prevent any backward movement of the projection 128 beyond the upper end of the latch. When the forward movement of the machine has been stopped, as described above, the stop dog 40 is in a raised position and the spring 43 is under extra compression. The spring 43 then reacts, forcing the stop dog 40 downward, causing the brake band to be turned slightly backward and with it the machine, until the projection 128 is stopped by the latch 130. The pressure of the spring 43 then holds the brake band contracted between the stop dog 40 and the latch 130, preventing any movement of the machine until it is started again by a downward movement of the treadle rod 47.

When the swinging member 64 is swung to disengage the stop dog 40 from the lug 38 to start the machine, the engagement of the ends of the brake band by the stop dog 40 and the latch 130 is released to permit rotation of the machine. It will thus be seen that the brake is released as the machine is started so that no unnecessary load is placed upon the driving means during starting and that the clutch is released when or before the brake is applied, so that no unnecessary load is placed upon the brake during stopping, thus overcoming a great fault of "Horton" clutch drives as heretofore constructed.

In order to simplify the foregoing description of the mechanism, a description of several adjustments has been omitted and these will be described below. These adjustments are for the purpose of overcoming those slight errors in manufacture which inevitably occur, for taking up wear of the parts and for providing for varying conditions met with in practice.

The stud 80 is eccentrically mounted in the extension 68 of the swinging member 64 in order that it may be made to strike the notched member 56 and give it the proper throw. This construction is shown in detail in Fig. 7, which is a sectional view taken at 7-7 in Fig. 5.

The latch 58 is mounted on an eccentric stud 132 secured to the frame of the machine by a set screw 133 and this provides an adjustment of the latch 58 which, in turn, determines the operative position of the member 64 so that the stop dog 40 will operate properly with the lug 38 of the clutch and with the projection 126 of the brake. This adjustable mounting of the latch is shown in detail in Fig. 8, which is a sectional view taken at 8-8 in Fig. 2.

The rod 42, upon which the stop dog 40 is mounted, may be raised or lowered by

turning the threaded portion 134 in the tapped hole in the extension 66 of the swinging member 64. When properly adjusted, the clamp bolt 136 secures it in position. By this adjustment, the time at which the stopping occurs may be adjusted as this determines the height of the shoulder 41 upon which the stop dog normally rests.

The operative position of the latch 130 is determined by the position of the stop screw 138 which is locked in position by the check nut 140. The strength of the spring 131 which returns this latch into operative position, after the projections 126 and 128 have passed under it, may be adjusted by means of the screw 142.

For convenience, in the following claims the term "manually operated means" is used to indicate any means under the control of the operator and may include, therefore, a hand lever, the usual treadle, a knee lever or any other device under the control of the operator, because the present invention is not limited to the usual form of operating treadle. Furthermore, in the claims the term "single cycle of operations" is used to refer to any complete cycle of operations of the machine which may be completed in either a single revolution, in a fractional part thereof or even in a plurality of revolutions, if more than one revolution of the driving means be required for completing a single cycle of operations. Accordingly, the invention is not limited to machines in which one cycle of operations is completed in one revolution of the machine, although, to avoid complication, it has been so described.

Having thus described the invention, what is claimed as new and desired to be secured by Letters Patent of the United States is:—

1. A starting and stopping mechanism comprising a driving member, a driven member, a clutch for connecting the driving and driven members, movable means under the control of the operator for rendering the clutch operative, and automatic means for disengaging the clutch at a predetermined point in the cycle of the driven member, said automatic means being operative when the movable means is moved to one position and being inoperative when the movable means is given a more extended movement to a second position.

2. A starting and stopping mechanism comprising a driving member, a driven member, a pair of brake members for stopping the driven member, movable means under the control of the operator for rendering the brake members inoperative, and automatic means for rendering the brake members operative at a predetermined point in the cycle of the driven member, said automatic means being operative when the mov-

able means is moved to one position and being inoperative when the movable means is given a more extended movement to a second position.

5 3. A starting and stopping mechanism comprising a driving member, a driven member, a clutch for connecting the driving and driven members, a pair of brake members for stopping the driven member, movable 10 means under the control of the operator for rendering the brake members inoperative and the clutch operative, and automatic means for disengaging the clutch and rendering the brake members operative at a 15 predetermined point in the cycle of the driven member, said automatic means being operative when the movable means is moved to one position and being inoperative when the movable means is given a more extended 20 movement to a second position.

4. A starting and stopping mechanism comprising a driving member, a driven member, a "Horton" clutch for connecting the driving and driven members, movable 25 means under the control of the operator for rendering the clutch operative, and automatic means for disengaging the "Horton" clutch at a predetermined point in the cycle of the driven member, said automatic means 30 being either operative or inoperative according to the extent of movement of the movable means.

5. A starting and stopping mechanism comprising a driving member, a driven member, a clutch for connecting the driving and driven members, movable means under the control of the operator for rendering the clutch operative, and automatic means for disengaging the clutch after a 40 predetermined movement has been given to the driven member, said automatic means being operative when the movable means is moved from normal to one position and being inoperative when the movable means is given a more extended movement to a second 45 position.

6. A starting and stopping mechanism comprising a driving member, a driven member, a clutch for connecting the driving and driven members, movable means under the control of the operator for rendering the clutch operative, and automatic means for disengaging the clutch after a predetermined movement has been given to the 55 driven member, said automatic means being operative when the movable means is moved from normal to one position and being inoperative when the movable means is given a more extended movement to a second position, said mechanism being ineffective to produce again the predetermined movement of the driven member until after the movable means has been returned to normal position.

65 7. A starting and stopping mechanism

comprising a driving member, a driven member, a clutch for connecting the driving and driven members, movable means under the control of the operator for rendering the clutch operative, automatic means for disengaging the clutch at a predetermined point in the cycle of the driven member, said automatic means being operative when the movable means is moved to one position and being inoperative when the movable means is given a more extended movement to a second position, and means for apprising the operator when the movable means is in a position to render the automatic means operative.

8. In a starting and stopping mechanism of the class described, a driving member, a driven member, means for connecting and disconnecting the driving and driven members, manually operated controlling means therefor comprising a member effective in one position to cause the driving member to impart a single cycle of operations only to the driven member and operating in another position to cause the driving member to impart repeated cycles to said member, and means effective when the first named position is reached for applying resistance to the movement of the controlling member in addition to the resistance necessary to be overcome to move it to said first-named position.

9. In a starting and stopping mechanism of the class described, a driving member, a driven member, means for connecting and disconnecting the driving and driven members, manually operated controlling means therefor comprising a member effective in one position to cause the driving member to impart a single cycle of operations only to the driven member and operating in another position to cause the driving member to impart repeated cycles to said member, and means effective when the first named position is reached for applying resistance to the movement of the controlling member in addition to the resistance necessary to be overcome to move it to said first-named position, said last-named means being constructed and arranged to remove said additional resistance upon return of the controlling member to its said first-named position.

10. A starting and stopping mechanism having, in combination, a brake drum secured to a shaft which is to be stopped, a brake band constructed and arranged to revolve therewith, mechanism for arresting the rotation of the brake band and effecting braking action thereof when power is withdrawn from the shaft, said mechanism including means acting to increase the braking action until the forward movement of the drum has been arrested.

11. In a starting and stopping mechanism

- of the class described, a shaft, a driving member and a driven member on said shaft, means for connecting and disconnecting said driven member and said driving member, a brake band constructed and arranged to revolve with the shaft when power is applied to the shaft, and mechanism for arresting the rotation of the brake band and causing it to be effective when power is withdrawn from the shaft, said mechanism being organized to vary the braking action with changes in speed. 65
12. In a starting and stopping mechanism, in combination, a brake drum secured to a shaft which is to be stopped, a brake band constructed and arranged to revolve with the shaft when power is applied to the shaft and to have a limited rotation relative thereto, and mechanism organized to arrest rotation of the brake band yieldingly and to cause the brake band to be contracted yieldingly, said mechanism operating to increase the braking action progressively until the shaft is stopped. 70
13. A starting and stopping mechanism, having, in combination, a brake drum secured to a shaft which is to be stopped, a brake band constructed and arranged to revolve therewith, yielding means for arresting the forward end of the brake band, yielding means for causing the rear end of the band to grip the brake drum, and means for continually increasing the gripping action until the forward movement of the drum has been arrested. 75
14. A starting and stopping mechanism, having, in combination, a brake drum secured to a shaft which is to be stopped, a brake band constructed and arranged to revolve therewith, yielding means for arresting the brake band, means for causing the band to grip the brake drum, means for increasing the gripping action until the forward movement of the drum has been arrested, and means for limiting backward movement of the brake band upon the reaction of said yielding means. 80
15. A starting and stopping mechanism, having, in combination, a driving member, a driven member, a clutch for connecting the driving and driven members, a brake drum mounted to move with the driven member, a brake band mounted to revolve with the brake drum and to have a limited rotation relative thereto, and a stop dog constructed and arranged so that in its operative position it will disengage the clutch and engage the brake band to stop the driven member, a brake band mounted to revolve with the brake drum and to have a limited rotation relative thereto, and a stop dog operating upon movement thereafter to its inoperative position to release the brake band and effect operative engagement of the clutch to re-start the machine. 85
16. A starting and stopping mechanism, having, in combination, a driving member, a driven member, a "Horton" clutch for connecting the driving and driven members, a brake drum mounted to move with the driven member, a brake band mounted to revolve with the brake drum and to have a limited rotation relative thereto, and a yielding stop dog constructed and arranged to disengage the clutch and thereupon to engage the brake band. 90
17. A starting and stopping mechanism, having, in combination, a driving member, a driven member, a "Horton" clutch for connecting the driving and driven members, a brake drum mounted to move with the driven member, a brake band mounted to revolve with the brake drum and to have a limited rotation relative thereto, a stop dog constructed and arranged to disengage the clutch and thereupon to engage the brake band. 95
18. A starting and stopping mechanism, having, in combination, a driving member, a driven member, a "Horton" clutch for connecting the driving and driven members, a brake drum mounted to move with the driven member, a brake band mounted to revolve with the brake drum and to have a limited rotation relative thereto, a stop dog constructed and arranged to disengage the clutch and thereupon to engage the brake band, and means for releasing the brake when the clutch is engaged. 100
19. A starting and stopping mechanism, having, in combination, a driving member, a driven member, a "Horton" clutch for connecting the driving and driven members, a lug projecting from one member of the clutch, a stop dog movable into and out of the path of movement of the lug, manually controlled means for moving the stop dog out of the path of movement of the lug to start the machine, automatic means for returning the stop dog into the path of movement of the lug, locking means to retain the stop dog in said path to stop the driven member if only a partial movement of the manually controlled means is made, and means to prevent the operation of the locking means upon a more extended movement 105 of the manually controlled means. 110
20. In a starting and stopping mechanism, in combination, a stop dog, a swinging member upon which the stop dog is yieldingly mounted, an extension on the swinging member, a latch for locking the swinging member to hold the stop dog in operative position, a shaft upon which the swinging member is loosely mounted, an arm fixedly mounted upon the shaft, a lever mounted upon the arm and having a plurality of notches, some one of which is engaged with the latch at all times, said lever being con- 115 120 125

structed and arranged to move the latch out of locking position upon a limited turning movement of the shaft carrying the lever, a stud, mounted upon the extension on the 5 swinging member, to engage the said lever and free the latch when the swinging member moves from locked position, and a cam for returning the swinging member to a position in which the stop dog will become 10 operative, the latch operating to lock the swinging member in position after this position has been reached.

21. In a starting and stopping mechanism, in combination, a stop dog, a swinging member upon which the stop dog is yieldingly mounted, a latch for locking the swinging member to hold the stop dog in operative position, a shaft upon which the swinging member is loosely mounted, an arm fixedly 15 mounted upon the shaft, a notched lever mounted upon the arm, a plurality of notches upon the lever some one of which is engaged with the latch at all times, the notched member being constructed and arranged to move the latch out of locking position upon a limited turning movement of the shaft carrying the lever, a stud mounted upon an extension of the swinging member to engage the notched member and free the 20 latch when the swinging member moves from locked position, and a cam for returning the swinging member to a position in which the stop dog will become operative, the latch operating to lock the swinging member in position after this position has 25 been attained, said parts being relatively constructed and arranged to prevent the swinging member from being locked with the stop dog in operative position upon a 30 more extended turning movement of the shaft carrying the lever and notched member.

22. In a mechanism of the class described, a shaft, a power pulley turning loosely on 45 the shaft, clutch mechanism for connecting the pulley to the shaft and for automatically disconnecting it therefrom, a starting lever, and connections between the starting lever and the clutch mechanism, said connections being operative, upon actuation of 50 the starting lever to a limited extent, to cause one revolution of the shaft to take place, and being operative, upon a more extended actuation thereof, to cause a plurality of such revolutions to take place.

23. In a mechanism of the class described, a shaft, a power pulley loosely mounted on 55 the shaft, a clutch for connecting the pulley to the shaft and for automatically disconnecting it therefrom, a starting lever, and clutch controlling mechanism, said mechanism being operative to connect the power pulley to the shaft for one or for a plurality of revolutions upon actuation of the start-

ing lever respectively through a short or 65 greater predetermined distance in initiating operation of the machine.

24. In a mechanism of the class described, a shaft, power means for driving the shaft, means for connecting the power means to the 70 shaft, a brake for the shaft, means operative to apply the brake at the end of a single revolution of the shaft, and means under the control of the operator for preventing the application of the brake at the end 75 of said single revolution.

25. In a mechanism of the class described, a shaft, a power pulley loosely mounted on the shaft, a clutch for connecting the pulley to the shaft, a brake for the shaft, means 80 for operating the brake to apply the same at the end of one revolution of the shaft, and means under the control of the operator for preventing the operation of the brake at the end of said one revolution.

26. In a mechanism of the class described, a shaft, a power pulley loosely mounted on the shaft, a clutch for connecting the pulley to the shaft, a starting lever for controlling the clutch so arranged that the extent of 90 movement of the starting lever determines whether one or more than one revolution of the shaft is to take place, a braking means for stopping the shaft, and means for preventing the application of the braking 95 means at the end of a single revolution when the clutch is set for a plurality of revolutions of the shaft.

27. In a mechanism of the class described, a shaft, a power pulley loosely mounted on 100 the shaft, a clutch for connecting the pulley to the shaft, a starting lever for controlling the clutch so arranged that the extent of movement of the starting lever determines whether one or more than one revolution of 105 the shaft is to take place, a braking means for stopping the shaft, and means under the control of the operator for preventing the application of the braking means at the end of a single revolution and for simultaneously 110 setting the clutch for a plurality of revolutions of the shaft.

28. In a mechanism of the class described, a shaft, a clutch on the shaft for connecting the latter to the source of power, a brake 115 operable to bring the shaft to rest, power means operative to apply the brake at a predetermined point in the revolution of the shaft, and a single operator controlled member for controlling the clutch to cause one 120 or a plurality of revolutions of the shaft and for simultaneously controlling the brake so that the latter is not applied until the end of the number of revolutions desired by the operator.

In testimony whereof I have signed my name to this specification.

WILLIAM C. STEWART.
